(57) **CLAIM**

The ornamental design for a planter reservoir, as shown and described.

DESCRIPTION

FIG. 1 is a perspective view of a planter reservoir showing my design used with a conventional five gallon bucket;

FIG. 2 is a top view of the planter reservoir shown in FIG. 1;
FIG. 3 is a bottom view of the planter reservoir shown in FIG. 1;

FIG. 4 is a side view of the planter reservoir shown in FIG. 1;
and

FIG. 5 is an exploded side view of the planter reservoir shown in FIG. 1; and,

FIG. 6 is an exploded perspective view of the planter reservoir shown in FIG. 1.

The broken lines showing a bucket in FIG. 1 form no part of the claimed design.
